AUTOMOBILE DOOR LATCH

William G. Creckett, Jr., Westlake, Ohio

Application August 19, 1950, Serial No. 180,490

1 Claim. (Cl. 292—300)

1

The present invention relates to a latch designed for latching a door to the body of an automobile. In ordinary door latches which simply prevent the door from springing open, the door often comes open when the automobile becomes involved in an accident. One of the reasons for this is that the heavy force of a person against the door will bend it, thus permitting the door lock to disengage. Many times, also, the post of the car set between the front and back doors may be pried away from one of the doors so that the ordinary door lock will disengage the lock and allow the door to spring open.

Therefore, one of the objects of the present invention is to provide a latch which will prevent the edge of the door from becoming pulled away from the car body.

Another object of the invention is to provide a door latch which has an outwardly extending member terminating in an upturned end and an outwardly extending portion with a downturned end wherein the members and ends have dimensions permitting movement of the door and the body relative to each other when the door is closed while possessing unimpaired holding power when sudden shock vibration is exerted against the door and the body.

Another object of the invention is to provide a door latch which may be used in conjunction with the standard door lock to safely hold the door closed against the automobile body.

Another object of the invention is to provide a door latch which will prevent the door from becoming separated from the body so that the door may spring open.

Another object of the invention is to provide an inexpensive safety lock for an automobile door which does not require any separate handles or other mechanism.

Other objects and a fuller understanding of this invention may be had by referring to the following description and claim, taken in conjunction with the accompanying drawing in which:

Figure 1 illustrates a top view of the latch mounted on the car door and body with the door and body illustrated in phantom;

Figure 2 is a sectional view along the line 2—2 of Figure 1;

Figure 3 is a sectional view along the line 3—3 of Figure 1; and

Figure 4 is a cross-sectional view along the line 4—4 of Figure 2.

The door latch illustrated herein has one part mounted on the body 10 of an automobile and

the other part mounted on the door 11 of the automobile. In the drawings, the body and the door have been illustrated in phantom lines since they may be from any automobile. The body 10 may also be the center post between the front and rear doors on an automobile. The part of the latch which is secured to the body or center post 10 is designated by the reference character 13, and the part which is fastened and secured to the edge of the door 11 is designated by the reference character 14. The drawings illustrate the parts in position when the door has been swung shut into the body 10 so that the door extends generally in the plane of the body 10 with the body part 13 of the latch on the edge of the body and the door part 14 of the latch on the edge of the door.

The body part 13 comprises a first vertical member 16 having a forward edge 17 and a rearward edge 18. The forward edge 17 would be that edge nearest the outside surface of the automobile. The vertical member 16 may be fastened to the car body by screws 19 or other suitable means. Extending outwardly from this first vertical member 16 is a first portion 20 which terminates in an upturned end 21.

In describing the present invention, the automobile door and body have arbitrarily been positioned in a vertical plane so that the first member 16 is in a vertical plane. The first portion 20 extends substantially transversely of that vertical plane or nearly in a horizontal plane. When the door and body are mounted in operable relationship the first portion extends in a slightly upward direction relative to the horizontal with the first portion being at the highest elevation nearest the rearward edge 18 of the first vertical member 16 and at the lowest elevation nearest the forward edge 17 of the first vertical member 16. This provides a sloping track 22 extending somewhat transversely of the first vertical member 16 from the forward edge 17 to the rearward edge 18 thereof.

The upturned end 21 is spaced further from the vertical member 16 at the forward edge than at the rearward edge thereby providing a wedge-shaped slot between the upturned end 21 and the first vertical member 16.

A second vertical member 25 is adapted to be attached to the door in alignment with the first vertical member, the second vertical member 25 being a part of the door mechanism part 14. This second vertical member 25 may be fastened to the edge of the door by screws 26 or other suitable means. The second vertical member is also

provided with a forward edge 27 and a rearward edge 28. A rider portion 29 extends outwardly from this second vertical member 25 and terminates in a downturned end 30. The rider portion 29 and the downturned end 30 are shaped to cooperate with the first portion 20 and the upturned end 21 of the body part 13. In other words, the body part 13 and the door part 14 have complementary overlapping and interlocking portions which may be the upturned end 21 and the downturned end 30. The downturned end 30 is spaced further from the second vertical member 25 at the forward edge 27 than at the rearward edge 28 and is also spaced from the second vertical member 25 a distance greater than the thickness of the upturned end 21 of the first vertical member 16. Likewise, the upturned end 21 is spaced a distance from the first vertical member 16 greater than the thickness of the downturned end 30 so that the ends 21 and 30 may be slid into complementary overlapping relationship when the door is closed against the body. The rider portion also extends in a slightly downward direction relative to the horizontal with the rider portion being at the highest elevation nearest the forward edge of the second vertical member. The rider portion is at the lowest elevation nearest the rearward edge of the second vertical member.

When the door is shut against the car body, the sloping of these portions on the first vertical member 16 and the second vertical member 25 permits the portions to take up any sag due to wearing of the hinges on the automobile door and thus the latch serves as a stabilizer. A spring backed vibration dampener 31 mounted on the first vertical member 16 pushes the rider portion 29 downwardly against the first portion 20 or the upturned end 21 to prevent rattling. The anti-rattler 31 may be of any standard design commonly used in door locks.

The present invention prevents edgewise moving of the door on the body away from the edge of the door or the edge of the body while the door 11 is maintained in the plane of the body 10. Any force which would attempt to snap the door away from the edge of the body 10 would simply be overcome by the complementary overlapping of the upturned end 21 and the downturned end 30. The door lock 32 illustrated in phantom in the drawings prevents the door 11 swinging or moving out of the body 10. This door lock 32 may be of any standard construction commonly used in present day automobile designs. The upturned and downturned ends 21 and 30 interlock the door 11 and the body 10 when the door 11 is closed into the general plane of the body 10 to move the forward edge 27 of the second vertical member 25 past the forward edge 17 of the first vertical member 16 and towards the rear edge 18 of the first vertical member 16.

Although this invention has been described in its preferred form with a certain degree of par-

ticularity, it is understood that the present disclosure of the preferred form has been made only by way of example and that numerous changes in the details of construction and the combination and arrangement of parts may be resorted to without departing from the spirit and the scope of the invention as hereinafter claimed.

I claim:

10 A latch for holding a door to a body comprising, a vertical first member having a forward edge and a rearward edge, a first portion extending outwardly from the first member and terminating in an upturned end, said upturned end having a top edge and being spaced further from said first member at the forward edge than at the rearward edge, said upturned end being spaced further from said first member at its intersection with said first portion than at its top edge, said first portion extending in a slightly upward direction relative to the horizontal with the first portion being at the highest elevation nearest the rearward edge of the first member, a vertical second member attached to the door in alignment with the first member and having a forward edge and rearward edge, a rider portion extending outwardly from the second member and terminating in a downturned end, having a bottom edge, said downturned end being spaced further from said second member at its intersection with said rider portion than at its bottom edge, said downturned end being spaced further from the second member at the forward edge thereof than at the rearward edge thereof and being spaced from the second member a distance greater than the thickness of the said upturned end, said rider portion extending in a slightly downward direction relative to the horizontal with the rider portion being at the highest elevation nearest the forward edge of the second member, and a resiliently backed pusher on said first member urging said rider portion and downturned end downwardly towards said first portion and said upturned end when the door is closed, said downturned end having a thickness less than the spacing of the upturned end from the first member and being spaced from the first member, thereby permitting movement of the door and body relative to each other when the door is closed.
